VARIABLE DISPLACEMENT PUMP OR
MOTOR

Elek K. Benedek, Bucyrus, Ohio

Application March 27, 1935, Serial No. 13,294

6 Claims. (Cl. 103—161)

This invention relates to variable delivery pumps and motors and is an improvement of the structure disclosed in my copending application Serial No. 738,184, filed August 3, 1934.

As therein more fully set forth, most rotary radial piston pumps and motors utilizing T-head pistons have certain desirable features which are offset, to some extent, by the frictional resistance developed between the T-heads and the reactance means and by heating of the parts due to localized stresses. Such resistance is due to the failure to maintain proper lubrication of the cooperating surfaces and also to the manner of transmitting both the torque and the load reactionary thrusts to and from the reactance and the piston heads.

Again, in pumps or motors of this type conjoint problems of assembly and the provision of a light but rigid and stable reactance with a very limited overall radial dimension are presented. The failure to solve these conjoint problems has limited the use and application of this type of pumps.

Some of the limiting factors are that these pumps require a larger radius of rotation to the outermost working parts with resultant concurrent increases in centrifugal force and peripheral speeds. Again, the mounting of the piston T-heads in the reactance so as to eliminate binding of the heads under hydraulic deflection has not been effectively solved. Proper cooperation of the piston crossheads and reactance for efficient torque transmission has been disregarded entirely. The required mass of the rotating parts, especially parts of the reactance means and the difficulty of lubricating the working parts efficiently likewise have resulted in decreases in efficiency. Again, failure to remove from the parts the heat resulting from flexure and friction, has reduced efficiency.

The principal object of the present invention is to provide, in a pump or motor of this character, completely anti-friction torque transmission, as well as anti-friction load transmission, for driving the reactance rotor.

A correlative object is to effect this result by maintaining a new cooperative relationship between the piston crossheads and the reactance rotor.

Another object of the present invention is to improve the construction of pumps of this particular type by greatly reducing frictional resistance and heating of the working parts.

Another object is to provide a piston T-head and mounting in which the T-heads are sub-

stantially no greater in width transversely of their path of travel than the diameters of the pistons themselves, whereby lateral bending stresses of the heads are substantially eliminated and the overall axial dimension of the pump and reactance assemblage may be reduced to a minimum.

Other objects are to provide for lightness of the working parts without a sacrifice of strength, for reduction of the radius of rotation of the parts and for elimination of localized binding and frictional stresses by more effective correlation of the working parts.

Other important objects are to provide effective lubrication of all the working parts while the pump is in operation, and to retain lubricant on the parts when the pump is inoperative for long intervals whereby, upon starting, the parts are fully lubricated.

More specific objects are to provide an improved reactance rotor and housing assembly whereby a more easily assembled, light, smaller diameter, rigid structure may be obtained.

Another specific object is to provide a novel T-head mounting as a result of which localized binding stresses are substantially eliminated and the radial dimensions of the head itself and of its mounting may be reduced, thus reducing the overall radius of rotation of the pump.

Another specific object is to provide a self-aligning control rod or lever for shifting the reactance rotor into different operating positions whereby assembly is facilitated.

Other objects and advantages will become apparent from the following specification wherein reference is made to the drawings in which

Fig. 1 is a horizontal sectional view through a pump or motor structure embodying the principles of the present invention and is taken on a plane indicated by the line 1—1 in Fig. 2;

Fig. 2 is a vertical cross sectional view of the pump or motor taken on a plane indicated by the line 2—2 of Fig. 1, part thereof being shown in elevation and part being taken on the plane indicated by the line 2a—2a of Fig. 1, for clearness in illustration;

Fig. 6 is a fragmentary sectional view of one of the piston heads and cooperating reactance means illustrated in Fig. 2 showing, in exaggerated condition, the relative position of the reactance means and head; and

Figs. 7 to 12, inclusive, are side elevations of a piston of the present structure illustrating, in exaggerated condition, the effects of various working stresses to which the pistons and T-heads are subjected under both load and torque transmission.

Referring to Figs. 1 and 2, the pump or motor comprises a bell shape housing 1 having a rigid hub 2 at one end and an integral axially extending circumferential wall 3 which forms the main body of the casing. The end of the casing remote from the hub 2 is closed by an end plate 4 through which extends the main impeller shaft 5 of the pump barrel, or delivery shaft in case 10 the apparatus is operated as a motor. Mounted by one end in the hub 2 and extending axially of the casing is a rigid valve pintle 6 which protrudes into the casing and is received in a dead end axial bore of the piston carrying rotor or barrel 7. The barrel 7 is rotatably mounted within the casing and held in accurate coaxial relation to the pintle by suitable sets of anti-friction bearings 8 arranged to withstand both axial and radial displacement of the barrel. The barrel 7 is provided with a series of circumferentially spaced radial cylinders 9, each of which is provided with a radial port 10 communicating with the interior of the barrel bore in position for cooperation with valve ports of the pintle 6.

35 The pintle is preferably of the hydrostatically balanced type, such as fully disclosed in my co-pending application Serial No. 754,853, filed November 26, 1934, and is provided with the usual pressure and suction ports 11 and 12 which successively communicate with the ports 10 of the barrel. The ports 11 and 12 communicate respectively with the usual longitudinal ducts 13 and 14 respectively, forming the necessary and well known fluid circuit of the pump. Also as 40 more fully set forth in my above identified co-pending application, hydrostatic deflection of the pintle is resisted and proper pintle lubrication is effected by suitable sets of capillary needle roller bearings 15a and 15b, spaced at opposite 45 ends of the valve portion of the pintle, respectively, and engaging bearing surfaces on the inner wall of the barrel bore. Received in each of the cylinders 9 are respective reciprocable pistons 16 each of which is provided at its outer end with a 50 T-head 20, as will be more fully described herein-after.

In order to reciprocate the pistons, a reactance rotor is provided. The reactance rotor comprises a pair of rings 25 and 26, the rings being coaxial and of equal diameters and mounted in axially spaced relation. A reactance housing 27 is provided for rotatably supporting the rings, the housing 27, in turn, having, at diametrically opposite portions, external plane bearing surfaces 28 cooperable with corresponding bearing surfaces in the body 3 for supporting the housing with its axis parallel to that of the barrel, while permitting shifting of the housing to different positions, either coaxial with the barrel or with 65 its axis eccentric and parallel to the barrel axis. On outer portions of the housing 27, at 90° to the bearing surfaces 28, are plane parallel stop surfaces 27a which are diametrically opposite with respect to each other and which cooperate 70 with corresponding plane surfaces 27b on the

interior of the body portion 3, for accurately limiting the setting of the housing 27 at maximum eccentricities to either side of the pintle axis. For supporting the rings 25 and 26 within the housing 27, anti-friction bearings 29 are provided. In the form illustrated in Fig. 1, two sets of bearings are shown, one set cooperating with the ring 25 and one with the ring 26. Annular troughs are provided on the inner face of the housing 27 and on the respective outer faces of the rings 25 and 26 for receiving the bearings and, through the medium thereof, rotatably mounting the rings 25 and 26 in the housing and retaining the rings in fixed axial position therein.

In larger pumps, such as illustrated, especially those in which ball bearings are used, care must be taken to eliminate heating, noise and wear of the bearings. Therefore, instead of the usual commercial design, the ball bearings 29 are loosely received between the housing and rings. The balls 29 are inserted by positioning the housing 27 eccentric with respect to the reactance rings 25 and 26 and the required number of balls is placed in the wider space thus afforded. The rings 25 and 26 are then brought concentric with the housing 27 by shifting the balls around the circumference. The balls are then spaced evenly by means of retainer rings 30, one ring being provided for each set. Each ring 30 comprises a pair of axially separable companion pieces secured together by suitable bolts 30a. The rings are of as little thickness radially as is practicable so as to be accommodated readily between the housing 27 and the reactance rings 25 and 26. The rings 30 are likewise of fibre for reducing the weight. The rings 30 separate the balls from each other, retaining them so that the balls are loosely fitted and may rotate at high speed unimpeded by excessive viscous friction between the balls or friction between the balls and retainer. The elimination of these frictional resistances, which are considerable in tight fitted or present commercial bearings due to displacement of the oil film, is very important. Furthermore, when the balls are thus loosely mounted, it is not necessary that they roll at all times while traveling about the inner race of the housing 27 but, on the contrary, only those directly under load need roll. Those not under load lie idly in an oil film similar to capillary needle bearings until carried to rolling position. Again, since the fibre rings 30 are light in weight and do not tightly engage the balls, the tangential and radial centrifugal forces imposed on the 55 balls thereby as they both roll and rotate about the rotary axis are greatly reduced with a concurrent increase in the efficiency of operation.

For shifting the housing 27, diametrically opposite radial control levers or rods 31 are provided, each of the levers being secured at its inner end to the housing. Suitable bores 3a are provided in the body portion 3, through which are received rigid tubular rods 32, the inner ends 32b of which abut the stop faces 27a of the housing 27. The rods 32 are generally coaxial with the rods 31 and surround the latter. Each of the tubular rods 32 is provided outwardly of the casing with an internal radial shoulder 32a, facing toward the outer end of the rod. The rods 31 extend outwardly past the shoulders 32a of the respective tubular rods and are provided with a suitable nut 33 having a shoulder overhanging the shoulder 32a. The shoulder 32a and nut 33 cooperate so that upon outward movement of 75

the rods 32, the inner rods 31 will be drawn therewith and upon inward movement of the rods 32, they will abut the housing and move it to the required position. The nut 33 is smaller than the inner passage of the tube 32 in which it lies, as also is the rod 31, so as to permit slight radial shifting and limited self-alignment of the rods 31 and 32. Obviously, as a result of the self-alignment of the rods 31 and 32 with respect to each other, and the end 32b of the rod 32 with respect to the housing 27, extreme care which otherwise would be necessary in manufacture and assembly is no longer required. The bores 3a do not have to be exactly diametrically opposite and coaxial, as slight misalignment will not cause binding of either the rods 31 or 32, nor, for the same reason do the threaded bores in the housing 27 in which the ends of the rods 31 are received have to be absolutely accurate in position with respect to each other or to the bores 3a. Again, since the end 32b of each rod 32 only abuts the housing, and since the rod 31 may shift relative to the rod 32, the housing 27 is not constrained to a fixed axial position in the body portion 3 thereby but may float a limited amount axially relative thereto. Again, whatever mechanism is provided for shifting the reactance rotor housing need not be accurately aligned with the bores 3a, as any slight axial misalignment or tilting will be compensated by shifting of the rods relative to each other. Likewise, axial compensation can be effected by screwing the nut 33 to desired positions along the rod 31.

35 Referring now more specifically to the piston T-heads and the manner in which they are operatively connected to the reactance rings, 25 and 26 for both torque and load transmission, each of the piston heads 20 protrudes tangentially of its path of rotation both forwardly and rearwardly from the axis of its associated piston and is elongated in the direction of travel. As set forth in my copending application, Serial No. 738,184, filed August 3, 1934, the T-heads, hereinafter referred to as heads or as crossheads, are preferably formed integral with the pistons with which associated. The central portions 20a of the crossheads are comparatively thick radially of the pump to withstand both the reactance 45 stresses resulting from the hydraulic load as well as the bending and warping stresses resulting from torque transmission. The width of the crossheads, that is, the dimension transversely of the path of rotation is the same or very slightly greater than the diameter of the pistons so that lateral overhang with consequent lateral bending stresses are substantially eliminated and the heads can be subjected only to lateral shearing stresses, all as will more fully appear hereinafter in the discussion of Figs. 7 to 12 inclusive. The radially outwardly disposed face of each head comprises a plane tangentially extending bearing surface, normal to the axis of its associated piston.

55 Since both rings 25 and 26 are the same in form and function, merely being placed oppositely with respect to each other, and since they cooperate with the piston heads in a corresponding manner, only the ring 26 and its relation to the piston head will be described in detail.

Referring to Fig. 2, at each piston there is provided on the ring 26 a primary roller 36, which extends parallel to the axis of the barrel or of the ring 26 and is positioned so as to intersect the axis of the piston with which it is associated when the barrel and ring 26 are set at zero eccentricity. In advance and to the rear of the pin 38, are secondary or torque transmitting rollers 37 and 38 respectively. The radial innermost surfaces of all of these rollers lie substantially in a common plane extending tangentially of the direction of travel. Thus each group of rollers 36, 37, and 38 define a substantially plane bearing surface cooperable with the outer bearing surface of a piston head 20 for driving the head on the pressure stroke or, in case of a motor, for transmitting the operating pressure stroke to the reactance, and for transmitting torque from the barrel to the reactance through the medium of the pistons and crossheads. As above mentioned, each of the piston heads 20 is provided with a thickened central portion 20a. The end portions, designated 20b, however, are of less thickness so that their inner surfaces are parallel to the outer bearing surface and constitute the inner bearing surfaces of the head. Correspondingly, torque rollers 39 and 40 are provided in the ring 26, the rollers 39 and 40 having their axes parallel to the rollers 37 and 38 and preferably being aligned therewith in planes therethrough and parallel to the axis of the associated piston. The rollers 39 and 40 engage the inner bearing surfaces of the end portions 20b respectively for moving the pistons on their suction strokes and for cooperating to transmit torque. The inner and outer sets of rollers, therefore, provide, in effect, substantially frictionless guides for transmitting reactions to and from the pistons while permitting the tangential oscillation of the piston heads relative to the reactance rotor for compensating for the tangential components of eccentricity of the barrel and reactance rotor. Since, as will be described more fully hereinafter, each piston crosshead is subject to warping under the combined effects of load and torque transmission, the rollers 37 and 39, and also the rollers 38 and 40, are actually spaced apart from each other a distance slightly greater than the radial thickness of the end portions 20b of the crossheads, for a purpose later to be described.

As illustrated in Fig. 2, the leading and trailing sets of rollers are equidistant from the piston axis.

Each of the rollers 36 is mounted at its ends in capillary cageless roller needle bearings, as indicated at 42, so that the rollers are freely rotatable about their respective axes.

For mounting the rollers while permitting ease in assembly and disassembly and for maintaining lubricant thereon, the rings 25 and 26 are provided with roller receiving bores 25a and 26a respectively, which bores extend parallel to the axis of the rings and terminate in dead end relation to the more remote ends of the rings. These bores open through the inner adjacent faces of the rings and corresponding bores of the respective rings are aligned axially with respect to each other. The bores 25a and 26a are provided with enlarged counterbores 25b and 26b, respectively, at their dead ends to allow axial clearance for the ends of the rollers 36. Each roller 36 has reduced bearing hubs 36a and 36b which are received in the bores 25a and 25b respectively in the capillary needle bearings. The torque rollers 37, 38, 39, and 40 are correspondingly mounted in needle bearings in corresponding aligned pairs of dead end bores in the rings 75

25 and 26 and correspond in shape to the rollers 36, but are less in diameter. The extreme ends of each of the rollers are of slightly greater diameter than the hub portions but are less in 5 diameter than the bores in which the pins are received so that they form the outer retainers to prevent axial displacement of the needle bearings. Thus the ends of the rollers and their 10 cooperating needle bearings may be inserted in their respective bores in the rings 25 and 26, and, when the rings are secured together in fixed 15 relation, as hereinafter described, the greater diameter roller portions of the rollers will hold the bearings in the bores. The rings 25 and 26 20 are spaced apart so as to receive, with a comparatively close but free sliding and capillary fit therebetween, the crossheads 20 of the pistons. Due to the reduction of radial dimensions 25 at the end portions 20b of the crossheads, the 26 rollers 39 and 40 may readily be accommodated in the rings 25 and 26 more closely to the axis of the piston with which associated without any increase in the radial width of the rings. Consequently, for a ring of given size, more space is 30 available between adjacent ends of adjacent heads for permitting installation of means for fastening rings 25 and 26 together.

Another advantage resides in making the end 35 portions of less thickness, in that the T-head is more nearly a constant strength beam and can flex more efficiently to permit substantially a complete transfer of all pressure reactance forces by and to the roller 36 and cooperate with the torque rollers for transmitting torque to the reactance rotor. The advantages of full strength 40 at the piston are also retained. As better illustrated in Fig. 2, between adjacent piston heads, there are provided in the rings 25 and 26, aligned bores extending parallel to the axis of the rings, 45 through which bores are received bolts 45 for fastening the rings 25 and 26 together. Each bolt 45 is in screw threaded engagement with the ring 26 and is provided with a head 44 which is snugly accommodated in a counterbore in the 50 ring 25 and engages a shoulder formed at the juncture of the bore and counterbore for drawing the rings relatively together. The counterbore is of sufficient depth so that no part of the bolt head 44 protrudes beyond the end of the 55 ring 25. As heretofore explained, it is necessary for efficient operation, that the working parts be effectively lubricated. Necessarily, during operation of the pistons, a certain amount of fluid 60 slip therest past occurs, this fluid traveling to the outer end of the pistons and their heads. In order to retain the proper spacing between adjacent faces of the rings 25 and 26 when assembled and to retain lubricant on the working parts, an annular circumferentially closed spacing ring 65 46 is provided, the ring 46 being slightly oversize axially relative to the width of the piston crossheads so that the rings 25 and 26 may be drawn against the ends of the ring in firm sealing engagement while permitting only capillary 70 clearances for the crossheads. When so fastened with the bolts 45, a deep circumferentially closed annular trough opening radially inwardly is provided in which the slip fluid is constrained against discharge by centrifugal force for maintaining sufficient lubricant on the heads and rollers. The dead end bores in which the hubs of the 75 rollers are received communicate with this trough for receiving lubricant therefrom.

Referring more specifically to the necessity for

and manner of accomplishment of proper lubrication, as mentioned above, the rollers for the crossheads are mounted in anti-friction capillary needle bearings. While the pump is operating, the slip from the pistons is thrown outwardly by 5 centrifugal forces and by the ring 46 is maintained in position for lubricating the working parts of the pumping assemblages. However, when the pump is temporarily shut down, this oil tends to drain by gravity to the bottom of the 10 pump body. If, after a considerable period, the pump were again started, the working parts would normally have no lubricant and, under the severe starting stresses, would be required to 15 operate with substantially no lubrication for an interval. The needle bearings, however, retain lubrication when the pump is shut down by the formation of capillary films so that upon starting 20 sufficient lubrication is present to lubricate the parts until the fluid slip again fills the trough. Correspondingly, some capillary film is maintained between the crossheads and adjacent faces of the rings 25 and 26. Though some lubrication 25 may be maintained on the bearings 29, these bearings, after one or two rotations of the pump, have passed to the lower part of the pump body and through the accumulated oil drained therein. Consequently, they are relubricated almost immediately.

The failure to provide for this lubrication or 30 maintenance of lubricant during the period in which the pump is shut down completely is one of the primary causes for rapid wear and failure. Necessarily, when the pump first begins operation, the power requirement for a given output, 35 due to inertia and frictional losses, is very high and when these must be withstood by substantially unlubricated piston heads, reactances, and moving parts, extreme wear and stresses, 40 often accompanied by immediate "freezing" of the working parts as well as excessive heating result. Even after the pump is in operation and lubricant is provided, the heating of the working 45 parts continues. As is well known, air spaces and the like constitute an effective insulating medium against heat transfer. With the annular trough and communicating bores for the rollers filled with fluid, this heat may readily be transmitted to the fluid from all the working parts and by it 50 carried or retransmitted to parts from which the heat can be more readily dissipated into the air or into the fluid passing through the pump.

Referring next to Figs. 4 and 5, modified forms 55 of reactance units for meeting special needs are illustrated, the parts therein corresponding to the same parts in Fig. 1, being numbered with corresponding primed and double primed numerals respectively.

Fig. 4 illustrates a reactance unit for use in 60 connection with the pump described having certain advantages over that shown in Fig. 1. This unit comprises companion reactance rings 25' and 26' mounted in a housing 27', these parts corresponding to the rings and housing in Fig. 1, and designated therein by corresponding unprimed numerals. The rings 25' and 26' are provided with sets of axially aligned bores 25a' and 26a' extending parallel to the axes of their rings. At the dead ends of the bores 25a' and 26a' the same 65 are counterbored, as indicated at 25b' and 26b' to slightly greater diameter and provide axial clearance between the end walls of the bores and the ends of the crosshead rollers to be received therein. On their radially outward surfaces, the rings 70

30

35

40

45

50

55

60

65

70

75

80

are provided with radially extending annular shoulders 50 and 52 respectively, the shoulders being positioned near the outer margins of the rings, respectively. Circumferential bearing surfaces extend from the shoulders entirely to the inner ends of the rings for receiving and mounting internal races 49 and 53 respectively of the ball bearings 29'. These internal races snugly embrace the circumferential surfaces of the rings and terminate at their inner ends flush with the inner ends of the rings on which they are carried. At their outer ends, the races firmly engage the shoulders 50 and 52 respectively. Disposed intermediate the rings is an annular circumferentially closed spacer ring 46' corresponding to the ring 46 heretofore described. The ring 46', instead of engaging the rings 25' and 26' directly engages the adjacent ends of the races 49 and 53, the ring 46' being slightly greater than the width of the piston heads so that the heads may be snugly received between the rings and maintain the capillary clearance therewith. For drawing the rings firmly together and into engagement with the ring 46' a series of circumferentially spaced bolts 45', each having a head 44' are provided, the ring 26' having a number of threaded bores to receive the threaded ends of the bolts 45' and the other ring 25' having corresponding bores for receiving the bolts. The bores in the ring 25' are counterbored to accommodate completely the heads 44' of the bolts. The housing 27' terminates at its ends in the planes of the outer ends of the rings 25' and 26' and is provided with internal circumferential axially extending surfaces which accommodate the outer races 48 and 51 of the bearings 29'. Intermediate the surfaces engaging the races 48 and 51, the housing 27' is provided with a radially inwardly extending circumferential boss 54 having, at each end, radial shoulders engageable with the inner ends of the races 48 and 51 respectively for limiting axial shifting of the races. The length of the boss 54 is slightly less than that of the ring 46'. Consequently, the rings 25' and 26' may be drawn firmly together against the spacer without danger of pinching the bearings 29' by axial offset of the inner races relative to the corresponding outer races, the outer races necessarily accommodating themselves in alignment with the inner races. The outer races, therefore, are, in effect, free floating within certain limits. If these provisions are not made, there is danger that the bearing will be gripped too tightly in the races and consequently will be destroyed almost immediately upon operation of the pump.

It should be noted that the bearings 29' are positioned directly over the bores 25a' and 26a' respectively so that the thrusts therefrom are transmitted directly to the crosshead rollers and bending moments are eliminated.

In some instances it is desirable to reduce the radial overall dimension of the unit, in which instance the unit illustrated in Fig. 5 is highly desirable. This unit is substantially the same in every way as the unit in Fig. 4 except that capillary needle bearings 29'' are utilized instead of the bearings 29' and greater relative axial movement between the housing and reactance rotor is afforded. In using the capillary needle bearings, no supplemental races are necessary. Instead, shallow circumferential troughs are provided on the exterior of the rings 25'' and 26'' in which the respective sets of needle bearings are disposed. The housing 27'', in turn, is provided

with internal circumferential bearing surfaces having no intervening boss corresponding to the boss 54 in Fig. 4. Thus the bearings 29'' with the rings 25'' and 26'' may shift axially relative to the housing 27''. Five distinct advantages are provided by this arrangement, namely; the rotary reactance formed by the rings 25'' and 26'' may shift axially with the primary rotor or barrel; the load transmitted through the bearings 29'' is transmitted over a distance axially of the rings substantially corresponding to the full length of the bearings in which the cross-head rollers are mounted in the bores 25a'' and 26a'' instead of being concentrated within relatively narrow limits; in addition to reducing the overall radial dimension, the bearings 29'' retain a capillary film while the pump is inoperative so that when it is again started, lubrication is present; the floating of the rings 25'' and 26'' relative to the housing 27'' permits the housing to shift to accommodate itself to the rings as the barrel is adjusted in operating position, and due to the relative self-alignment of the control rods 31'' and 32'', efficient control may be provided therefor in the shifted condition. Lastly, in assembling the pump, it is only necessary to place the pistons in the barrel cylinders, drop the torque and load rollers in their bores respectively in one of the reactance rings, position the piston heads between their rollers, place the spacer 46'' in place, and clamp the other reactance ring firmly against the spacer 46'', and then, after placing the needle bearings 29'' in position, slide the housing 27'' therearound. The assemblage of the reactance unit and pump barrel may then be slid into place in the body of the pump and the barrel fixed in proper position, the reactance rings necessarily adjusting themselves in proper axial position relative to the barrel. The housing 27'' may then be shifted axially to the extent necessary for connecting the control rods 31'' and 32'' thereto.

Referring next to the piston crossheads and their cooperation with the load and torque rollers, these actions are fully illustrated in Figs. 7 to 12 inclusive. In Fig. 10, is illustrated a normal piston and integral crosshead substantially full size, in unloaded condition, both so far as concerns hydrostatic load and torque transmission. The median line of the crosshead is designated $x=10$ and the center line of the piston designated $y=10$. It is pointed out that both lines $x=10$ and $y=10$ are straight lines lying 90° to each other.

In Fig. 7, the condition of the piston under maximum hydraulic load and without any effects of driving torque, is illustrated, the force to which the piston is subjected being designated by P . In Fig. 7, it is assumed that the center load roller 36 is removed or that P is so great that its influence will deflect even the load roller until the end portions of the crosshead come in contact with the rollers 37 and 38. Thereupon the median line $x=1$ of the crosshead will become curved, defining a parabolic curve of the second order under the influence of the reactionary forces R . The centerline $y=1$ of the piston remains undisturbed and straight.

Referring next to Fig. 8, the piston is shown under the influence of driving torque only, this torque, designated M_1 , is being imposed on the piston through the cylinder bore wall by the forces $Q-Q$. This couple or moment must be resisted and is, in fact, resisted by the reactionary forces T , one of which forces is transmitted to

- the crosshead by one of the outer rollers 37 or 38 and the other is transmitted by one of the inner rollers 39 or 40 at the opposite side of the piston axis from the active one of the rollers 37 and 38.
- 5 The driving moment or couple M_1 will distort the piston itself so that the centerline $y-8$ thereof becomes curvilinear. The reaction couple M_2 , however, will distort and warp the crosshead, theoretically, in the manner illustrated, so that
- 10 the median line $x-8$ of the crosshead becomes a reverse curve, reversing at the centerline $y-8$ of the piston. This curve will be necessarily a curve of the third order, that is, defined by an equation having one of its unknowns raised to the third power. The effects illustrated in Fig. 8 are due to torque transmission alone and not to load transmission. This condition may occur, for example, at full stroke operation when the transmitting power and torque are great enough to
- 15 stress the piston and crosshead. It may also occur without the application of maximum pressure as in those cases in which the pintle becomes too tight in the barrel or some pair of barrel bearings become too tight.
- 20 25 In Fig. 9, the combined effects illustrated in Figs. 7 and 8 are shown, this combined effect being produced when the piston is at maximum pressure and maximum torque, as when the pump is operating under full stroke and full pressure to provide maximum power. The piston centerline $y-9$ is the graphic addition of the lines $y-7$ and $y-8$; and the median line $x-9$ of the crosshead is a graphic addition of lines $x-7$ and $x-8$ of Figs. 7 and 8. It is apparent that these two 30 separate and distinct forces, namely: load and torque transmission, result in not only warping the crosshead itself but in twisting it backward relative to the normal axis of the piston. It is also flexed outwardly intermediate its ends by the hydrostatic load at the same time the piston is deformed by the couple M_1 , which is the driving couple. It should be noted that since the forces and power developed by each piston are very great and the piston dimensions relatively small, 35 the lever arms through which the couples M_1 and M_2 are developed are relatively small. As a result the forces producing the couples necessarily are correspondingly large and, in fact, are of considerable magnitude. For a piston such as 40 illustrated in the figures, the force P is about 3000 pounds, or one and one half tons, the reaction forces $R-R$ being correspondingly great. The driving forces are about one tenth as great, or 300 pounds, so that they are of secondary 45 magnitude as compared with the primary forces P . It is apparent, therefore, that the pistons and heads tend to twist and break apart. While the load roller 36 tends to offset to some extent the deflection caused by the force P , it hardly 50 affects the couples M_1 and M_2 .
- 55 In Figs. 11 and 12, the cooperation between the piston crossheads and the torque rollers is illustrated more specifically, this again being the cooperation only insofar as torque transmission is concerned. From Fig. 11 it is apparent that by cooperation of the rollers 37 and 40 with the corresponding opposite ends of the crosshead, torque may be transmitted positively and by direct thrust even while maintaining anti-friction 60

1. In a rotary radial piston pump or motor of the character described, including a barrel, circumferentially spaced pistons carried thereby, a reactance rotor eccentric to the barrel for reciprocating the pistons consequent upon concurrent rotation of the barrel and rotor, heads respective to the pistons, each head protruding tangentially of its path of travel in both directions from the piston with which it is associated and having tangential outer bearing surfaces and inner bearing surfaces at the end portions, said surfaces being parallel with respect to each other, load rollers carried by the rotor, each roller being in rolling engagement with the outer face of the piston head with which associated normally at the axis of the particular piston for moving the piston on the pressure stroke while permitting tangential oscillation of the head with respect to the reactance rotor, torque transmitting rollers carried by the rotor and engaging the inner bearing surfaces of the heads respectively for moving the piston on the suction stroke, each head being concurrently in rolling engagement with both the outer and inner rollers associated therewith, additional torque rollers carried by the rotor and engaging the outer surface of the heads respectively adjacent the zone of the said inner rollers, said additional rollers being spaced from the inner rollers a distance slightly greater than the radial thickness of the portion of the head received therebetween for permitting free deflection of portions of the head and for guiding the head while in the deflected condition.
2. In a rotary radial piston pump or motor of the character described, including a barrel, circumferentially spaced pistons carried thereby, a reactance rotor eccentric to the barrel for reciprocating the pistons consequent upon concurrent rotation of the barrel and rotor, heads respective to the pistons, each head protruding tangentially of its path of travel in both directions from its associated piston and having a tangential outer bearing surface and tangential spaced inner bearing surfaces parallel to said outer surface, said inner bearing surfaces being at opposite sides of the piston axis, outer central and end rollers carried by the reactance rotor and spaced longitudinally of the head and engaging the outer surface of the head both at its central portion and end portions, and additional inner rollers carried by the rotor and engaging the inner bearing surfaces of the head, said outer end rollers and inner rollers being spaced apart a distance slightly greater than the radial dimension of the end portions of the head for permitting inward flexure of the head by the outer central roller, unconstrained by the outer end rollers.
3. In a pump or motor of the character described, including a barrel and radial piston assemblies carried thereby, and a reactance rotor eccentric to the barrel and cooperable with the piston assemblies for reciprocating the same consequent upon concurrent rotation of the barrel and rotor, said rotor comprising coaxial axially spaced matched rings, a circumferentially closed annular spacer received therebetween and coaxial therewith, the ends of the spacer engaging said rings outwardly from their radial inward margins in fluid sealing engagement therewith, whereby a circumferentially closed trough is formed, companion dead end bores in said rings parallel to the common axis thereof, said coaxial bores being in pairs, each opening toward the other and through the adjacent spaced face of the other ring with which associated, piston-actuating rollers having their ends received in said bores, one roller to each pair of bores, each roller having a central roller portion and end portions protruding therefrom, means for securing the rings in fixed coaxial position in sealed relation with the spacer with said pin end portions of the rollers in said dead end bores, said dead end bores being of greater diameter than the said ends of the rollers for receiving cageless rollers for rotatably supporting the piston actuating rollers, the roller portions of the piston actuating rollers being larger in diameter than the portions which engage the cageless rollers and being coextensive axially with the space between the rings, whereby, when the rings are secured together, the piston actuating rollers are mounted therein and the cageless rollers are retained in operating condition by the rollers.
4. In a pump or motor of the character described having a piston carrying barrel, a reactance rotor, and a reactance rotor housing and means mounting and guiding the housing for movement to different positions while retaining the housing with its axis parallel to the axis of the barrel, a control rod for moving the housing, said control rod comprising a rigid tubular rod abutting, at its inner end, the said housing and extending radially outwardly therefrom, and parallel to the guide means, means mounting the tubular rod for axial movement parallel to the guide means, a rigid rod loosely received within the tubular rod and fixedly connected at its inner end to the housing, said tubular rod having an internal radially extending shoulder facing away from the housing, said rigid rod protruding away from the housing beyond said shoulder, and means on the protruding portion of the rigid rod having a shoulder overlying the said radial shoulder and securing said rods for outward movement together, and said means being less in size than the portion of the tubular rod in which it is located, whereby the rods may shift relatively radially and compensate for slight axial misalignment of the rods.
5. In a rotary radial piston pump or motor of the character described, including a barrel, circumferentially spaced pistons carried thereby, a reactance rotor eccentric to the barrel for reciprocating the pistons consequent upon concurrent rotation of the barrel and rotor, heads respective to the pistons, each head extending tangentially of its path of travel in both directions from its associated piston and having a tangential outer load bearing surface at the central portion of the head and outer torque bearing surfaces at the end portions of the head, and tangential spaced inner bearing surfaces parallel to said outer surfaces at the end portions of the head, load transmitting means carried by the reactance rotor and in load transmitting engagement with the load bearing surface, and torque transmitting means spaced longitudinally of the head and engaging the outer torque surfaces of the head, and additional inner torque transmitting means carried by the rotor and engaging the inner torque surfaces of the head, the associated outer and inner torque transmitting means being spaced apart parallel to the piston axis a distance slightly greater than the spacing of the load transmitting means and the inner torque transmitting means.
6. In a pump or motor of the character described having a barrel, an adjustable reactance, piston and cylinder assemblies and means mount-

5 ing and guiding the adjustable reactance for movement to different adjusted positions while retaining the reactance with its axis parallel to the axis of the barrel, means extending through the casing for adjusting the reactance, said means comprising a tubular rod abutting the reactance at its inner end and extending radially outwardly therefrom generally parallel to the guide means, said casing having a radial passage snugly ac-

commodating said tubular rod, a second rod connected to the reactance and lying within the first tubular rod with clearance radially of the rods, and means connecting the rods for axial movement together and limited radial movement concurrently, whereby the rods may shift relatively radially of each other and compensate for axial misalignment. 5
